UNITED STATES PATENT OFFICE.

MATHIAS ZINSMAYER, OF CLEVELAND, OHIO.

BEVEL-PROTRACTOR.

1,125,628.

Specification of Letters Patent. Patented Jan. 19, 1915.

Application filed March 18, 1914. Serial No. 825,599.

To all whom it may concern:

Be it known that I, MATHIAS ZINSMAYER, a citizen of the United States, residing at Cleveland, in the county of Cuyahoga and State of Ohio, have invented new and useful Improvements in Bevel-Protractors, of which the following is a specification.

This invention relates to bevel protractors, the primary object being to provide a device of this character which includes an elongated, rectangular body which forms a handle, a movable blade connected pivotally and slidably with the body and readily operable and positive means whereby the blade 10 may be adjusted angularly with respect to the body and may be secured in adjusted position, irrespective of the sliding adjustment of the blade, which is to increase or decrease the effective length thereof.

20 A further object is to provide a device of the class set forth wherein the means for securing the movable blade in adjusted position is of such character that the blade may be set at a predetermined angle accurately 25 without observing the scale provided for the purpose. The device may thus be used efficiently even after the scale has been rendered indistinct or has been obliterated by long use and exposure to the deteriorating 30 action of damp air or the like.

The invention consists in the features of construction, combination, and arrangement of parts, hereinafter fully described and claimed, reference being had to the accompanying drawings, in which:

Figure 1 is a side elevation of the device, showing the movable blade in its inoperative position, folded within the body slot; Fig. 2 is a longitudinal sectional view 40 taken vertically through the device; Fig. 3 is a longitudinal sectional view on line 3—3 of Fig. 2; Fig. 4 is a transverse sectional view on line 4—4 of Fig. 1; Fig. 5 is a similar sectional view on line 5—5 of Fig. 2; Fig. 6 is a top plan view of the device, showing the movable blade in one of its angularly adjusted, operative positions, other positions of the blade being shown in dotted lines; Fig. 7 is a detail bottom plan

view of the movable gear; and Fig. 8 is a detail perspective view of the body of the device.

In the drawings, the numeral 1 designates the elongated rectangular body of the device which is provided in one of its side faces with a longitudinal recess 2, Fig. 5, whereby the weight of the body is reduced and it is adapted to be grasped more securely when being used. The opposite side face of the body is provided at one end thereof with an enlargement 3 whose inner end face 4 is beveled at an angle of 45° to the longitudinal axis of the body. The body is adapted to be cast from aluminum, or some other light and durable metal, and a flat, resilient plate 5 of tempered steel or the like is secured to the outer side face of the body enlargement 3 detachably, as by means of the screws 6. This plate 5 extends longitudinally with respect to the body and is disposed normally in parallel relation to the adjacent side face thereof. The end of the body 1 adjacent to the free end of the plate 5 is provided in its inner face with a circular recess 7, which opens through the rounded end face of the body and is arranged with its axis at right angles to the longitudinal axis of the body. The corresponding end of the plate 5 is also rounded similar to the said end face of the body and both this plate and the body are provided with alining openings concentric with the recess 7, the body opening being threaded for the reception of one end of a detachable pivoting stud 8, whose opposite end projects through the plate opening and is threaded for the reception of a knurled binding nut 9. A pair of coacting crown gears 10 and 11 are adapted to be mounted within the body recess 7 upon the stud 8. The intermeshing teeth of each gear are standard teeth and are arranged at a pitch of 7° 30' for reasons which will appear presently. The gear 10 is fixedly secured to the body by means of screws 12, but the coacting gear 11 is rotatable upon the stud under certain conditions and has its outer flat face flush with the adjacent side face of the body 1 for even

engagement with the adjacent face of a movable blade 13, which latter is mounted within the slot afforded between the body 1 and the plate 5. The said blade is constructed so as to fit completely within the said slot when in its inoperative position, as shown particularly in Figs. 1 to 5 of the drawing, and is provided with a longitudinal slot 14 receiving the radially extending lug 15 which is formed upon the outer flat face of the crown gear 11. The fixed and movable crown gears are provided upon their outer peripheries with the co-operative scale 16 of angular measurement and an indicator line 16^a respectively, which are inscribed thereon in any suitable manner, for use in determining the degree of angular adjustment of the movable blade. The blade is also provided upon one of its side faces 20 with a scale of linear measurement 17 coextensive with its longer edge.

Owing to the fact that the teeth of the crown gear have a pitch of $7^{\circ} 30'$, the movable blade 13 may be adjusted accurately to any of the ordinarily employed angles to the longitudinal axis of the body. The degree of adjustment may be determined by reference to the scales 16, and this operation is accomplished by merely turning the blade and the crown gear 11, which is rotatable therewith, upon the stud 8 as a pivot, after the binding nut 9 has been loosened upon the stud. The resilient plate 5, which normally tends to maintain the gear teeth in mesh, will thus be sprung laterally to release the movable gear and to permit the desired angular adjustment of the same. The limiting lug 15 carried by the movable gear is adapted to prevent pivotal movement of the blade 13 with respect to the said gear, but allows limited sliding movement thereof as is necessary in varying the effective length of the blade. The said lug is constructed slightly thinner than the movable blade in order that it will not contact with the resilient plate 5. Therefore, the nut 9 will force the plate end firmly against the movable blade alone, thereby binding the same effectively against sliding movement. The movable blade may thus be adjusted longitudinally and may be secured in adjusted position without affecting the angular relation of the same to the body.

The angular adjustment of the movable blade with respect to the body may be effected without reference to the scale, for, as the gear teeth slip past each other, they will make a clicking sound, by which the number of teeth slipped may be determined readily. For each click there will be an adjustment of $7^{\circ} 30'$, so, when it is desired to adjust the movable blade 15° from any given position, two teeth will be slipped and consequently two sharp clicks will be audible.

The usual angles of adjustment, such as 30° , 45° , 60° , and 90° , may be obtained readily in this manner. Therefore, the sides of square, octagonal, and hexagonal figures may be described accurately with the instrument when its movable blade is properly set. Each gear will have 48 teeth in order to afford a pitch of $7^{\circ} 30'$, but it may prove desirable to provide gears having a pitch of 5° so they may be constructed with 72 teeth each. If it is found desirable to use the instrument in drawing pentagons, each gear must be provided with 240 teeth, thereby having a pitch of $1^{\circ} 30'$.

From the foregoing description, taken in connection with the accompanying drawings, it should be apparent that I have provided a bevel protractor which is extremely simple in construction, is composed of few parts, and is adapted to be used accurately and efficiently by carpenters, and other artisans, in the well known capacities of such an instrument.

What is claimed is:

1. A bevel protractor comprising a body, a transverse pivot stud provided within the body, a movable blade mounted upon the said stud for oscillatory and radial sliding movement thereon, a fixed crown gear mounted upon the body concentric with the stud, a second crown gear mounted pivotally upon the stud and being adapted to mesh with the fixed gear, and means for connecting the movable blade with the movable gear to prevent relative rotary movement thereof.

2. A bevel protractor comprising a body, a transverse pivot stud provided within the body, a movable blade mounted upon the said stud for oscillatory and radial sliding movement thereon, a fixed crown gear mounted upon the body concentrically with the stud, a second crown gear mounted pivotally upon the stud and being adapted to mesh with the fixed gear, means for connecting the movable blade with the movable gear to prevent relative rotary movement thereof, and means for securing the movable blade against radial movement with respect to the movable gear.

3. A bevel protractor comprising a body, a lateral pivoting stud provided within the body, a crown gear mounted concentrically upon the said stud and being connected fixedly with the body, a second crown gear pivotally mounted upon the stud in mesh with the fixed gear, an elongated radially extending lug formed upon the outer flat face of the movable gear, and a movable blade mounted within the body and having a longitudinal slot receiving the pivoting stud and the said gear lug.

4. A bevel protractor comprising a body, a lateral pivoting stud provided within the body, a crown gear mounted concentrically upon the said stud and being connected fix-

edly with the body, a second crown gear pivotally mounted upon the stud in mesh with the fixed gear, an elongated radially extending lug formed upon the outer flat face of the movable gear, a movable blade mounted within the body and having a longitudinal slot receiving the pivoting stud and the said gear lug, and means for securing the mov-

able blade against radial movement with respect to the movable gear. 10

In testimony whereof I affix my signature in presence of two witnesses.

MATHIAS ZINSMAYER.
